UNITED STATES PATENT OFFICE.

ROBERT E. FRAME, OF MICHIGAN CITY, INDIANA.

DRAFT-GEAR.

1,093,392.

Specification of Letters Patent. Patented Apr. 14, 1914.

Application filed November 6, 1913. Serial No. 739,479.

To all whom it may concern:

Be it known that I, ROBERT E. FRAME, a citizen of the United States, and resident of Michigan City, county of Laporte, and State of Indiana, have invented certain new and useful Improvements in Draft-Gears, of which the following is a specification, and which are illustrated in the accompanying drawings, forming a part thereof.

10 The invention relates to draft gears for railway cars of the so-called friction type.

The object of the invention is to secure a high degree of efficiency, and to provide for a progressive development of the frictional resistance by bringing the elements into action successively. These objects are attained by the construction illustrated in the accompanying drawings, in which:

Figure 1 is a side elevation of the gear partly in section; Fig. 2 is a transverse vertical central section through the gear; and Figs. 3, 4 and 5 are plan sections of the gear showing it in different positions.

The gear is illustrated as being applied 25 to a railway car, there being shown a pair of draft sills 10, 11, provided with draft lugs 12, 13, 14 and 15 of any desired form. The gear inclosed within a yoke 16, here shown as of the conventional type and as being attached to the butt of the coupler 17 by means of rivets, and there is present a supporting plate 18, bolted to the draft sills and upon which the yoke rides, and a tie-plate 19 uniting the draft sills above the 30 gear. These parts do not appertain to the invention, and may take any form as desired.

The gear comprises a pair of front and rear casings 20, 21, of box form. The two 40 casings are alike, and each is provided with a pair of shoulders 22, 23, 24, 25, for engaging the draft lugs 12, 13, and 14, 15, respectively. The forward casing 20 bears against the butt of the coupler 17, and the 45 rearward casing against the rear end of the yoke 16. Housed within each of the casings is a pair of springs 26, 27, and 28, 29, arranged one within the other, though, if desired, a single spring only may be used with 50 each casing. These springs are seated against the inner ends of the casings and react against followers 30, 31. Each of these followers has a flat face for engaging the springs, and a pair of inwardly inclined wedging 55 faces which coöperate with triangular friction blocks 32, 33, 34, 35 respectively. Be-

yond the inner ends of the springs the walls of the casings flare, as shown at 36, 37, 38, 39, to form wedging surfaces for engaging the outer faces of the triangular blocks. 60

Interposed between the forward triangular blocks 32, 33, and the rearward triangular blocks 34, 35, there is a compressible abutment comprising a pair of laterally movable wedging elements, generally designated by the numerals 40, 41. The last-named elements are chambered, and there is located between them a spring 42 which urges them apart. The side walls 43, 44, 45 and 46 of the members 40, 41, are inclined inwardly and toward the ends of the gear, and frictionally engage the third sides of the triangular blocks 32, 33, 34 and 35. At the outer ends of their inclined side walls the members 40, 41, are provided with shoulders 47, 48, and 49, 50, and intermediate of these shoulders the outer ends of the members extend outwardly, providing inclined faces 51, 52, 53 and 54. 70

The inner ends of the side walls of the 80 casings 20, 21, extend beyond the inclined portions 36, 37, and 38, 39, a short distance parallel with the axis of the gear, as shown at 55, 56, and 57, 58,—these parallel portions engaging, respectively, the shoulders 85 47, 48, and 49, 50. The extreme portions of the inner ends of the side walls of the casings flare outwardly, as shown at 59, 60, 61 and 62, these outwardly flaring portions engaging the inclined portions 51, 52, 53 90 and 54 of the members 40, 41, during the final compressive movement of the gear. The outer surfaces of the walls of the casings may be provided with strengthening ribs, as shown at 63, 64, and the members 95 40, 41, are provided with internal webs, as shown at 65, 66, for the purpose of increasing their strength and providing seats for the spring 42.

When the gear is in release position, as 100 shown in Fig. 3, the shoulders 22, 23, and 24, 25, of the casings are in engagement with the draft lugs 12, 13, and 14, 15. The parallel portions 55, 56, and 57, 58, of the walls of the casings are in engagement with the outer ends of the shoulders 47, 48, and 49, 50, of the members 40, 41. As either of the casings is advanced both slide upon these shoulders (the abutment being moved longitudinally toward the stationary casing) 105 until the parts assume the position of Fig. 4,—the outwardly inclined portions 59, 60,

and 61, 62, of the inner ends of the side walls of the casings coming into contact, respectively, with the inclined portions 51, 52, and 53, 54, of the ends of the members 40, 41. Meantime the triangular wedge-blocks have been forced inwardly, crowding back the followers 30, 31. Further advance of the casing causes the outwardly inclined portions of their walls 59, 60, and 61, 62, to slide upon the inclined portions 51, 52, and 53, 54, of the outer ends of the members 40, 41, forcing these members inwardly and compressing the spring 42.

Initial friction is developed mainly between the triangular wedge-blocks and the inclined walls of the casings and the followers 30, 31, there being also some friction developed between the wedging blocks and the side walls of the members 40, 41. During the final movement of the casings friction is developed between the inclined ends of both of the casings and the inclined ends of the members 40, 41, and between the side walls of these members and the triangular blocks.

The action is the same in both pulling and buffing, and while but one casing moves in either instance the wedging action is identical at the two ends of the gear.

30 All of the springs coöperate in effecting the release and returning the parts to their normal position, this release, however, being retarded by the frictional engagement of the various members, thereby preventing shocks.

35 I claim as my invention—

1. In a draft gear, in combination, a pair of opposed casings, a pair of spring-separated laterally movable members having inclined outer ends, spring seated within the casings, and wedging elements interposed between the springs and the laterally movable members, the end portions of the walls of the casings being inclined and engageable with the inclined ends of the laterally movable members.

2. In a draft gear, in combination, a pair of opposed casings, a pair of spring-separated laterally movable members having inclined outer ends, springs seated within the casings, and wedging elements interposed between the springs and the laterally movable members, the end portions of the walls of the casings being inclined and engageable with the inclined ends of the laterally movable members but normally spaced apart therefrom.

3. In a draft gear, in combination, a pair of casings having their side walls flaring, a laterally compressible abutment between the casings, springs seated within the casings, a set of wedging elements interposed between each spring and the abutment, the outer ends of the abutment and of the side walls of the casings having coöperating inclined surfaces normally out of engagement.

4. In a draft gear, in combination, a pair of casings, a laterally compressible abutment between the casings and comprising a pair of chambered members whose outer ends are wedge-shaped and a spring urging such members apart, springs seated within the casings, and a set of friction elements located between each of the last-named springs and the abutment, the ends of the side walls of the casings being outwardly inclined and engageable with the wedge-shaped ends of the abutment members.

5. In a draft gear, in combination, a central laterally compressible abutment comprising a pair of chambered members, the ends of such members having shoulders parallel to the line of draft and outwardly inclined surfaces intermediate of such shoulders, a pair of casings having their side walls provided with parallel portions engaging the shoulders of the abutment members and inclined portions engageable with the inclined portions of the ends of such members, springs seated within the casings, and friction elements located between such springs and the abutment.

6. In a draft gear, in combination, a central laterally compressible abutment comprising a pair of chambered members, the ends of such members having shoulders parallel to the line of draft and outwardly inclined surfaces intermediate of such shoulders, the side walls of such members being inclined inwardly and toward the ends of the gear, a pair of casings having their side walls provided with parallel portions engaging the shoulders of the abutment members and inclined portions engageable with the inclined portions of the ends of such members, springs seated within the casings, and friction elements located between such springs and the abutment.

7. In a draft gear, in combination, a pair of casings each having its side walls outwardly inclined, such inclined portions being interrupted by portions parallel to the line of draft, springs seated in the casings, wedging elements seated on the springs, triangular blocks bearing on the faces of the wedging elements and the inner portions of the inclined side walls of the casings, and a laterally compressible abutment having inclined side walls engaging the triangular blocks, the ends of the abutment having flat shoulders engaging the parallel portions of the side walls of the casings and inclined faces intermediate of such shoulders.

8. In a draft gear, in combination, a longitudinally movable casing, a laterally compressible abutment, normally engaged coöperating bearing surfaces parallel with the line of draft on the casing and abutment, and outwardly inclined coöperating faces on said members coming into engagement during the final movement of the casing, and

cushioning elements within the casing and bearing against the abutment.

9. In a draft gear, in combination, two sets of cushioning elements each comprising 5 springs and friction members, and a laterally compressible friction member interposed between the two sets of cushioning elements and compressively engaged therewith after the initial action thereof, such abutment comprising a pair of chambered casings and a spring housed within and reacting between the casings.

10. In a draft gear, in combination, a movable casing, a spring housed within the 15 casing, a laterally compressible abutment, friction elements interposed between the spring and the abutment, the casing having an initial non-compressive and a final compressive engagement with the abutment, 20 such abutment comprising a pair of chambered casings and a spring housed within and reacting between the casing.

11. In a draft gear, in combination, a longitudinally movable casing, a laterally compressible abutment, such abutment comprising 25 a pair of chambered casings and a spring housed within and reacting between the casing, normally engaged co-operating bearing surfaces parallel with the line of 30 draft on the casing and abutment, and outwardly inclined co-operating faces on said members coming into engagement during the final movement of the casing, and cushioning elements within the casing and bearing 35 against the abutment.

12. In a draft gear, in combination, a longitudinally movable casing having flaring side walls, two pairs of laterally movable friction elements having inclined surfaces 40 engageable by the inclined walls of the casing successively, and means resisting the inward movement of the members of each pair of friction elements.

13. In a draft gear, in combination, a longitudinally movable casing having flaring side walls, two pairs of laterally movable friction elements having correspondingly inclined surfaces, the inclined walls of the casing being normally engaged with such surfaces of one of the pairs of friction elements 45 and engaging such surfaces of the other pair of friction elements during the final move-

ment of the casing, and means resisting the inward movement of the members of each pair of friction elements. 55

14. In a draft gear, in combination, a longitudinally movable casing having flaring side walls, two pairs of laterally movable friction elements having inclined surfaces engageable by the inclined walls of the casing successively, members of each pair of friction elements having contacting faces oblique to the axis of the gear, and means resisting the inward movement of the members of each pair of friction elements. 60 65

15. In a draft gear, in combination, two longitudinally movable casings having their open ends facing and their side walls flaring, a pair of inwardly movable friction elements housed within each casing and having inclined faces in constant engagement with the side walls of the casings, a third pair of inwardly movable friction elements interposed between and engaging the first-mentioned pairs of friction elements and having oppositely inclined surfaces engageable by the inclined walls of the casings only during the final compressive movement of the gear, and means for urging all of the friction elements outward. 70 75 80

16. In a draft gear, in combination, two longitudinally movable casings having their open ends facing and their side walls flaring, a pair of inwardly movable friction elements housed within each casing and having inclined faces in constant engagement with the side walls of the casings, a third pair of inwardly movable friction elements interposed between and engaging the first-mentioned pairs of friction elements and having oppositely inclined surfaces engageable by the inclined walls of the casings only during the final compressive movement of the gear, a spring housed within each casing, a wedge-shaped follower seated on each spring and 85 entering between the members of the pairs of inwardly movable friction elements, and a spring reacting between the two members of the third pair of friction elements. 90 95
